UNITED STATES PATENT OFFICE.

ERNEST GLASS, OF READING, PENNSYLVANIA.

GEARING.

1,427,374.

Specification of Letters Patent. Patented Aug. 29, 1922.

Application filed August 8, 1921. Serial No. 490,622.

To all whom it may concern:

Be it known that I, ERNEST GLASS, a citizen of the United States, residing at Reading, in the county of Berks and State of Pennsylvania, have invented certain new and useful Improvements in a Gearing; and I do hereby declare the following to be a full, clear, and exact description of the invention, such as will enable others skilled in the art 10 to which it appertains to make and use the same.

This invention relates to gearing whereby an intermittent reverse rotary movement is converted into a continuous rotary movement in either a clockwise or counterclockwise direction as desired.

Specifically considered the invention relates to an improvement in the gearing disclosed in U. S. Patent No. 1,378,781, granted 20 me the 21st day of May, 1921, for a rotary tooth brush.

The present invention simplifies the gearing disclosed in my prior patent and renders the same more positive and certain in 25 action.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to 35 without departing from the nature of the invention.

Referring to the accompanying drawings forming a part of the specification,

Figure 1 is a detail view of a rotary tooth 40 brush embodying the invention.

Figure 2 is a sectional detail of the casting, the brush being omitted and the parts being shown on a larger scale.

Figure 3 is a sectional detail of the gear- 45 ing.

Figure 4 is a section on the line $x-x$ of Fig. 2, and

Figure 5 is a detail.

Corresponding and like parts are referred to in the following description and

designated in the several views of the drawings by like reference characters.

The numeral 1 designates a suitable frame or casing which constitutes a housing for the gearing. A drive shaft 2 is suitably mounted within the housing or frame 1. A gear wheel 3 is fast to the drive shaft 2 and is provided at one side with a hub 4.

A spiral spring 5 is fast at one end to the hub 4 and is connected at its opposite end to the frame 1 and is adapted to be wound by rotation of the gear wheel 3 in one direction.

A tape 6 or like element is attached at one end to the hub 4 and is wound thereon and extends through an opening 60 formed in a side of the frame 1.

When the tape or like part 6 is drawn upon it is unwound from the hub 4 and imparts rotary movement to the gear wheel 3 and at the same time tensions the spring 5 by winding 65

the same upon the hub 4. When the tape or like part 6 is relaxed the spring 5 comes into play and rotates the gear wheel 3 in a reverse direction and rewinds the tape 6

upon the hub 4.

A ring 7 or like part is mounted in axial alinement with the drive shaft 2 and is provided at its outer edge with ratchet teeth 8 adapted to cooperate with a dog 9 whereby the ring 7 is held stationary during the 80 rotation of the drive shaft 2 in one direction. The ring or part 7 is provided with gear elements 10 which are in meshing relation with the teeth of the gear wheel 3.

A rotary member 11 is loose on the drive shaft 2 and is provided with gear teeth 12 and 13, the teeth 12 being in mesh with the teeth of the gear elements 10 and the teeth 13 being in mesh with the teeth of gear elements 14 and 15 loosely mounted 85

upon a driven shaft 16 which drives the parts to be rotated. The rotary member 11 is provided upon one side with clutch teeth 17 which cooperate with correspond-

ing teeth of a spring actuated clutch member 18 splined to the drive shaft 2. When the gear wheel 3 is rotated by a direct pull upon the tape or like part 6, the member 11 is correspondingly rotated through the 90

instrumentality of the clutch member 18.

95

100

During this movement the ring or part 7 is free to rotate with the parts 3 and 11. Upon a reverse rotation of the gear wheel 3 and drive shaft 2 under the action of the spring 5, the ring or part 7 is held stationary by the teeth 8 and dog 9 and the gear elements 10 being in mesh with the teeth of the gear wheel 3 are rotated thereby and positively transmit motion to the part 11 in the same direction. During this action the teeth of the clutch member 18 ride upon the clutch teeth 17. It will thus be understood that the part 11 is continuously rotated in the same direction by an intermittent reverse rotary movement imparted to the drive shaft 2 and gear element 3 rotatable therewith. In the preferable construction the several gear elements are of the bevel type although it is to be understood that they may be of any structural form.

The driven shaft 16 is disposed at right angles to the drive shaft 2 and projects from the frame or housing 1 and is provided at its outer end with a tooth brush 19 or other part to be rotated. A housing 20 attached to the frame 1 receives the shaft 16 which is mounted at its outer end therein. The gear elements 14 and 15 are loose on the shaft 16 and each is provided upon its inner side with clutch teeth 21. A clutch member 22 splined on the shaft 16 is movable between the gear elements 14 and 15 and is adapted to be thrown into clutch engagement with either. A shipper member 23 mounted in the frame or casing 1 is in cooperative relation with the clutch member 22 whereby the latter may be moved to a neutral position or into clutch engagement with either one of the gear elements 14 or 15 so as to rotate the shaft 16 in the desired direction. The shaft 16 may be rotated continuously in a clockwise or counter-clockwise direction according to which one of the gear elements 14 or 15 is in clutch engagement therewith. A pull upon the tape or part 6 unwinds it from the hub 4 and rotates the gear 3 in one direction and at the same time winds the spring 5. This effects positive rotation of the member 11 through the clutch 17 and 18. When the part 6 is relaxed the spring 5 comes into play to rotate the gear element 3 in a reverse direction thereby rewinding the part 6 and positively rotating the gear elements 10 which in turn effect a rotation of the part 11 in the same direction, the clutch 17 and 18 slipping during this action. During the reverse rotation of the gear element 3 the part 7 supporting the gear elements 10 is held stationary hence the action of the gear elements 10 in transmitting motion from the parts 3 to the parts 11.

Having thus described the invention, what I claim is:—

1. In gearing of the character specified, a drive shaft, means for imparting an intermittent reverse rotary movement to the drive shaft, a gear wheel rotatable with the drive shaft, a rotary member in axial line with the drive shaft, a ratchet clutch between the rotary member and drive shaft, a gear element having toothed engagement with said rotary member and gear wheel, a rotary support for the gear element loosely mounted in axial line with the rotary member and gear wheel and a ratchet connection for holding said support stationary on the rotation of the drive shaft in one direction and during the slipping action of the clutch connection between the said rotary member and drive shaft. 65

2. In gearing of the character specified, a drive shaft, means for imparting an intermittent reverse rotary movement to the drive shaft, a gear wheel fast to the drive shaft and rotatable therewith, a rotary member loosely mounted in axial line with the drive shaft, a ratchet clutch between the rotary member and drive shaft, a gear element forming connecting means between said gear wheel and rotary member, a rotary support for the gear element loosely mounted in axial line with the gear wheel and rotary member and a ratchet connection for holding the rotary support stationary during the rotation of the drive shaft in one direction. 85

3. In gearing of the character specified, a drive shaft, means for imparting an intermittent reverse rotary movement to the drive shaft, a gear wheel fast to the drive shaft, a rotary member loose on the drive shaft, a rotary support loosely mounted intermediate said gear wheel and rotary member, gear elements mounted on the rotary support and having toothed connection with the said gear wheel and rotary member, a ratchet connection between the rotary support and a relative stationary member to prevent rotation of the support during movement of the drive shaft in one direction and a ratchet clutch between said rotary member and drive shaft to cause said parts to rotate in unison with said rotary support. 100

4. In gearings of the character specified comprising drive and driven shafts, means for imparting intermittent reverse rotary movement to the drive shaft, a gear wheel fast to the drive shaft, a rotary member loose on the drive shaft, a ratchet clutch between the rotary member and drive shaft, a rotary support loosely mounted in axial line with the drive shaft, a ratchet connection for holding the rotary support station- 120

125

ary during the rotation of the drive shaft in one direction, gear elements mounted on the rotary support and having toothed engagement with said gear wheel and rotary member, gear elements loose on the driven shaft and having toothed connection with said rotary member and a clutch member splined on the driven shaft and adapted to be thrown into clutched engagement with

either one of the gear elements loose 10 thereon.

In testimony whereof I affix my signature in presence of two witnesses.

ERNEST GLASS.
